(57) **CLAIM**

The ornamental design for a laundry bag, as shown and described.

DESCRIPTION

FIG. 1 is a front elevational view of a laundry bag showing my new design;

FIG. 2 is a rear elevational view thereof;

FIG. 3 is a side view, taken from the left side of FIG. 1;

FIG. 4 is a side view, taken from the right side of FIG. 1;

FIG. 5 is a top plan view thereof; and,

FIG. 6 is a bottom plan view thereof.

The cross-hatching shading in the figures is fragmentarily shown for convenience of illustration, it being understood that the shading is uniformly continued over the surface in which it appears.

The broken line showing the ties in FIGS. 1 and 5 is for illustrative purposes only and forms no part of the claimed design.
